UNITED STATES PATENT OFFICE.

FREDRICK S. STAFFORD, OF CHICAGO, ILLINOIS, ASSIGNOR TO STAFFORD AUTO LAMP & NUMBER COMPANY, OF CHICAGO, ILLINOIS, A CORPORATION OF TEXAS.

DESIGN FOR A VEHICLE-LAMP.

46,455.

Specification for Design.

Patented Sept. 22, 1914.

Application filed July 25, 1914. Serial No. 853,171. Term of patent 7 years.

To all whom it may concern:

Be it known that I, FREDRICK S. STAFFORD, a citizen of the United States, residing at Chicago, in the county of Cook and State of Illinois, have invented a new, original, and ornamental Design for Vehicle-Lamps, of which the following is a specification, reference being had to the accompanying drawing, in which—

Figure 1 is a top plan view; Fig. 2 is a side elevation; and Fig. 3 is an end view.

I claim:

The ornamental design for a vehicle lamp substantially as shown.

FREDRICK S. STAFFORD.

Witnesses:

LEWIS T. GREIST,
E. H. POLLARD.
